TREATMENT OF HYDROCARBON OILS

Lyman C. Huff, Chicago, Ill., assignor to Universal Oil Products Company, Chicago, Ill., a corporation of Delaware

Application August 28, 1937, Serial No. 161,403

3 Claims. (Cl. 196—11)

This is a continuation-in-part of my co-pending application Serial No. 113,424 which was filed on November 11, 1936.

The invention relates to an improved method of fractional distillation which is particularly directed to the efficient and economical separation of hot vaporous hydrocarbons, such as those resulting from the pyrolytic conversion of hydrocarbon oils, into selected heavy fractions boiling above the range of gasoline, selected high-boiling gasoline fractions of low vapor pressure, stabilized light gasoline fractions and normally gaseous products.

The invention is not directed to any specific feature of the process herein disclosed, but resides in a novel arrangement of cooperative and interdependent steps, each of which contribute to the final desired results.

The process will be explained in detail in conjunction with the accompanying diagrammatic drawing which illustrates one specific form of apparatus in which the process may be conducted. The novelty and advantages of the invention will be more apparent from the following description of the drawing.

Relatively hot vaporous hydrocarbons, such as those resulting from the pyrolytic conversion of hydrocarbon oils to produce therefrom high yields of good quality gasoline, are supplied from any desired type of cracking system, not illustrated, through line 1 and valve 2 to fractionator 3 wherein their high-boiling fractions, preferably comprising substantially all of the components of the vapors boiling above the range of the desired gasoline product, are condensed as reflux condensate. Suitable fractionating means, not illustrated, such as bubble trays, packing, perforated pans or the like or any desired combination of such well known means, are provided in fractionator 3 and preferably one or more relatively cool liquid hydrocarbons is supplied, as will be later described, to the fractionator to directly commingle therein with the vaporous products undergoing fractionation and serve as a cooling and refluxing medium.

The total reflux condensate formed in fractionator 3 or selected relatively heavy fractions thereof may be removed from the lower portion of this zone through line 4 and valve 5 and may be recovered, after cooling by well known means, not illustrated, as a final product of the process or may be directed, by well known means, not shown, to any desired further treatment such as, for example, further cracking in the same cracking system from which the heated vaporous prod-

ucts subjected to said fractionation are derived, or in separate cracking apparatus of any desired form, not illustrated.

In case it is desired to separate the reflux condensate formed in fractionator 3 into selected fractions of different boiling characteristics, this may be accomplished within the fractionator by removing only high-boiling fractions of the reflux condensate from the lower portion of this zone, as above described, and separately removing one or more selected lower boiling fractions from one or a plurality of suitable intermediate points in the fractionator. Lines 6 and valves 7 are provided for this purpose in the case here illustrated and a selected relatively low-boiling fraction or fractions thus removed from the fractionator may be cooled by well known means, not illustrated, and recovered as a final product of the process or subjected to any desired further treatment either within the cracking system from which the vaporous products subjected to said fractionation are derived or in a separate system of any desired type.

The invention provides for introducing hydrocarbon oil charging stock for the cracking operation from which the vapors subjected to said fractionation are derived into fractionator 3 at any desired point or plurality of points in this zone by means of line 8 and branch lines 9 and 10, controlled, respectively, by valves 11 and 12. By this method of operation, a regulated portion or all of the charging stock is directly commingled with the relatively hot vaporous products undergoing fractionation, serving to partially cool and assist said fractionation of the vapors. Also, by this method of operation, any components of the charging stock boiling within the range of the desired overhead vaporous product from fractionator 3 will be vaporized and commingled with the vaporous conversion products of like boiling characteristics, while the higher boiling components of the charging stock will commingle with the reflux condensate formed in fractionator 3 and, when the latter is separated into selected low-boiling and high-boiling fractions, the charging stock is also subjected to the same separation.

Fractionated vapors of the desired end-boiling point, which include normally gaseous products and materials boiling within the range of the desired gasoline product of the process, and which may, when desired, also include somewhat higher boiling materials such as heavy naphtha fractions, kerosene, kerosene distillate, pressure distillate bottoms, or the like, are removed from the upper portion of fractionator 3 and directed through

line 13 and valve 14 to further fractionation, as will be later described, in fractionator 15.

In order to provide a suitable light refluxing and cooling medium for use in the upper portion of fractionator 3, a regulated quantity of the fractionated vapors removed from the upper portion of this zone are directed from line 13 through line 16 and valve 17 to cooling and partial condensation in condenser 18. The resulting uncondensed gases and the uncondensed low-boiling fractions of the vapors supplied to condenser 18 are directed therefrom through line 19 and valve 20 to collection and separation in accumulator 21. Distillate collected in accumulator 21 is withdrawn therefrom through line 22 and valve 23 to pump 24 by means of which it is recirculated in regulated quantities through line 25 and valve 26 to the upper portion of fractionator 3 wherein it serves as a cooling and refluxing medium for maintaining the desired vapor outlet temperature from the fractionator and controlling the end-boiling point of the overhead vaporous stream from this zone. The vapors and gases which remain uncondensed in accumulator 21 are removed therefrom through line 27, either alone or together with any distillate collected in this zone in excess of that required as a cooling and refluxing medium in fractionator 3, and this material may be directed from line 27 through line 28 and valve 29 to further fractionation in fractionator 15, or, in case only uncondensed vapors and gases are removed from accumulator 21 through line 27, they may, when desired, be directed through valve 30 in line 27 to further cooling and partial condensation in condenser 44, the function of which will be later described, or, they may be directed from line 27 through line 31 and valve 32 to further cooling and condensation in sub-coolers 57 and 57', which will be later described.

The vaporous and gaseous materials supplied to fractionator 15, as previously described, are further fractionated in this zone to separate the same into low-boiling vaporous components, consisting of light gasoline fractions of the desired end-boiling point and normally gaseous products, and a higher boiling condensate comprising heavy gasoline fractions and, when desired, also including somewhat higher boiling materials such as previously mentioned.

In order to substantially free the reflux condensate formed in fractionator 15 of dissolved normally gaseous products and light fractions boiling within the range of the desired overhead vaporous product from fractionator 15, said reflux condensate is preferably reboiled either within or external to fractionator 15 in any well known manner such as, for example, by the introduction of steam or by passing this reflux condensate in indirect heat exchange with a suitable heating medium such as steam or, preferably, relatively hot oil, oil vapors or gases derived from within the cracking system. In the case here illustrated, provision is made for passing a suitable heating medium in indirect heat exchange with the reflux condensate in the lower portion of fractionator 15 by means of line 33, valve 34, closed coil 35, line 36 and valve 37.

The reboiled reflux condensate, substantially free of dissolved gases and undesired low-boiling fractions, is removed, in the case here illustrated, from the lower portion of fractionator 15 through line 40 and valve 41 and may be directed therefrom to cooling and storage, not illustrated, or to any desired further treatment. The reflux condensate thus removed from fractionator 15

comprises, as previously mentioned, high-boiling gasoline fractions and due to the fairly high temperature at which this material may be recovered from fractionator 15 and the fact that it may be substantially freed of entrained gases and undesired low-boiling components by simple reboiling, these heavy gasoline fractions will not require stabilization to reduce their vapor pressure but may require chemical treatment to reduce their sulfur content, gum content and/or improve their color or gum, color and antiknock stability. Any such further treatment of these high-boiling gasoline fractions is definitely within the scope of the invention, although it is not concerned with the specific method whereby they are further treated and the latter is, therefore, not illustrated. The invention also contemplates reforming of the heavy gasoline fractions recovered from fractionator 15 in case the same are of unsatisfactory antiknock value, this being accomplished by subjecting the heavy gasoline fractions to cracking conditions of high temperature at substantial superatmospheric pressure regulated to materially improve the antiknock characteristics of the gasoline fractions without excessively altering their boiling range. When reforming of the heavy gasoline fractions is required, the vaporous products supplied from fractionator 3 to fractionator 15 may, when desired, include materials such as previously mentioned, boiling somewhat above the range of gasoline, which higher boiling materials are susceptible to further cracking under conditions suitable for reforming of the heavy gasoline fractions to produce additional yields of good quality gasoline from said heavier fractions. In such cases, said heavier fractions are condensed as a portion of the reflux condensate in fractionator 15 and supplied to the reforming step, not illustrated, together with the high-boiling gasoline fractions.

Fractionated vapors of the desired end-boiling point, which consist of normally gaseous products and light gasoline fractions, are directed from the upper portion of fractionator 15 through line 42 and valve 43 to cooling and partial condensation in condenser 44. The resulting distillate and uncondensed vapors and gases are directed from condenser 44 through line 45 and valve 46 to collection and separation in accumulator 47. The distillate collected in accumulator 47 is returned in regulated quantities by means of line 48, valve 49, pump 50, line 51 and valve 52 to the upper portion of fractionator 15 wherein it serves as a cooling and refluxing medium for assisting fractionation of the vapors and maintaining the desired vapor outlet temperature from the fractionator, thus controlling the end-boiling point of the light gasoline product recovered from fractionator 15.

The vapors and gases remaining uncondensed in accumulator 47 are removed therefrom, either alone or together with any distillate collected in this zone in excess of that required as a cooling and refluxing medium for fractionator 15, and, in the case here illustrated, this material is directed from accumulator 47 through line 55 and valve 56 to and through sub-coolers 57 and 57' wherein it is cooled to a lower temperature than that employed in condenser 44 whereby to condense substantially all of its normally liquid components. Although two sub-coolers are illustrated in the drawing, one or any desired number of a plurality of such zones may be employed and

they may be of any desired form. In the case here illustrated, a suitable cooling medium is supplied to sub-cooler 57' to line 53 and valve 59 and is directed from this zone through line 60 and valve 61 to sub-cooler 57 wherefrom it is discharged through line 62 and valve 63. The materials undergoing cooling and condensation pass, in the case here illustrated, through sub-coolers 57 and 57', in series, counter-current to the general direction of flow of the cooling medium through each of these zones, line 64 containing valve 65 being provided for transferring the materials cooled and partially condensed in sub-cooler 57 to further cooling and condensation in sub-cooler 57'.

The distillate and uncondensed normally gaseous products resulting from the cooling and condensation accomplished in sub-coolers 57 and 57' are directed from the latter zone through line 66 and valve 67 to collection and separation in receiver 68. The uncondensed gases which remain undissolved in the distillate are released from receiver 68 through line 69 and valve 70.

The distillate collected in receiver 68 will ordinarily contain a substantial quantity of dissolved normally gaseous products in excess of those required to produce a distillate of the desired vapor pressure. This light gasoline product is, therefore, preferably subjected to stabilization for the purpose of reducing its vapor pressure to the desired degree by liberating any excess of dissolved gases therefrom. This is accomplished, in the case here illustrated, by removing the distillate from receiver 68 through line 71 and valve 72 to pump 73 by means of which it is directed through line 74, valve 75, heat exchanger 76, line 77 and valve 79 to stabilizer 79, the operation of which will be later explained.

The purpose of heat exchanger 76 is to reheat and partially vaporize the distillate prior to its introduction into the stabilizing column, this being accomplished by passing the distillate in indirect heat exchange with a suitable heating medium comprising, for example, steam, hot oil or oil vapors or gases either from within the system or from an external source. The heating medium is supplied to heat exchanger 76, in the case here illustrated, through line 80 and valve 81 and is removed therefrom through line 82 and valve 83.

It will, of course, be understood that any other well known method of reheating and partially vaporizing the distillate to be subjected to stabilization, prior to or after its introduction into the stabilizing column, may be employed within the scope of the invention.

Stabilizer 79 may comprise any well known form of stabilizing equipment and, in the case here illustrated, it is a column provided with bubble trays, packing or the like, not illustrated, whereby efficient contact between the ascending vapors and gases and the descending liquids is accomplished.

Preferably, only a portion of the heat required for stabilization of the distillate is accomplished in heat exchanger 76, the remainder being provided by supplying heat from an external source to the liquid accumulating in the lower portion of the stabilizer by any well known means, not illustrated, or by reboiling this liquid in a reboiler external to the main stabilizing column. In the case here illustrated, the liquid to be reboiled is supplied from the lower portion of column 79 through line 86 and valve 87 to reboiler 88 wherein it comes in indirect heat exchange with a suitable heating medium which is passed

through closed coil 89 in reboiler 88, the heating medium being supplied to coil 89 through line 90 and valve 91 and discharged therefrom through line 92 and valve 93. The vapors and gases evolved from the distillate by reboiling in reboiler 88 are returned therefrom through line 94 and valve 95 to stabilizing column 79. The reboiled distillate comprising light gasoline fractions stabilized to the desired vapor pressure is removed from reboiler 88 through line 96 and valve 97 to cooling and storage or to any desired further treatment and regulated quantities of this material may, when desired, be utilized as the heating medium in heat exchanger 76, the hot reboiled distillate being directed to heat exchanger 76 from reboiler 88 by well known means, not illustrated.

Preferably, to assist in establishing equilibrium conditions in stabilizer 79 and provide a liquid refluxing medium in this zone by condensing vaporous products in the upper portion thereof, suitable cooling means are provided in the upper portion of the stabilizing column. In the case here illustrated, such cooling means comprise a closed coil 98 through which any desired cooling medium may be circulated, the latter being supplied to coil 98 through line 99 and valve 100 and removed therefrom through line 101 and valve 102. The normally gaseous products liberated from the distillate and remaining uncondensed in the stabilizer 79 are released from the upper portion of this zone through line 103 and valve 104 and may be directed therefrom to absorption, storage or elsewhere, as desired.

The stabilized light gasoline fractions recovered from the stabilizing step, as previously described, may, when desired, be subjected to chemical treatment or purification for the purpose of reducing their sulfur and/or gum content or improving their color, gum and antiknock stability. Any such further treatment, although not illustrated, is within the scope of the invention and one of the numerous advantages of the process herein provided resides in the separate recovery of stabilized light gasoline fractions and a heavier gasoline fraction which does not require stabilization, whereby either of these fractions may be subjected to any desired further treatment in the absence of the other or whereby the two fractions may be subjected to different treatments selected to suit the particular requirements of each. As a specific example, the heavy gasoline fractions recovered from fractionator 15 may be treated to improve their color and reduce their gum content by contacting the same in heated liquid state at superatmospheric pressure with a suitable porous clay, such as fuller's earth or the like, while the light gasoline fractions recovered from fractionator 15 may be stabilized and thence blended, without further treatment, with the refined heavy gasoline fractions to form the final full-boiling-range gasoline product of the process. As another specific example, the reflux condensate formed in fractionator 15 may contain any high-boiling gasoline fractions which are of unsatisfactory antiknock value and may also include some heavier fractions boiling up to approximately 520° F., for example, this reflux condensate being subjected to reforming conditions of high cracking temperature and superatmospheric pressure regulated to produce high yields of good antiknock gasoline, the latter being subjected to stabilization in column 79, together with the low-boiling gasoline fractions of satisfactory antiknock value separately recovered

from fractionator 15 and the resulting stabilized gasoline being recovered as the final motor fuel product of the process which may, when required, be treated with an inhibitor, such as relatively small quantities of wood tar fractions, to prevent deterioration of its color, gum and anti-knock characteristics.

As a special feature of the invention, in addition to the treatment, as previously described, of the vaporous conversion products supplied to fractionator 3 through line 1 and valve 2, the system may be utilized for the simultaneous and similar treatment of light hydrocarbon oil distillate from an external source, consisting of or containing a substantial quantity of gasoline or gasoline fractions. This distillate may be, for example, straight-run gasoline or naphtha, gasoline or pressure distillate from a separate cracking system or any desired combination of such materials. The distillate may be supplied to the system either in preheated or relatively cold state and may be introduced either into fractionator 3 or into fractionator 15, although these alternatives are not to be considered equivalent. Provision is made in the case here illustrated for directing distillate, such as previously mentioned, from an external source, through line 110 wherefrom it may be directed into fractionator 3 at any desired point in this zone through one or a plurality of branch lines 111 controlled by valves 112. Provision is also made in the apparatus here illustrated for supplying distillate, such as previously mentioned, from an external source, to fractionator 15 through line 113 and valve 114, the same being introduced into fractionator 15 at any desired point in this zone.

When gasoline or gasoline-containing distillate from an external source is supplied, as described, to fractionator 3, it may serve to partially cool and assist fractionation of the vaporous conversion products in this zone and is subjected to fractionation therewith, in the manner previously described. In such cases, the components of the distillate boiling within the range of the desired overhead vaporous product are vaporized in fractionator 3 and directed therefrom to further fractionation, in the manner previously described, in fractionator 15, while any higher boiling fractions of the distillate commingle with the reflux condensate formed in fractionator 3 and are recovered or subjected to further treatment, as the case may be, with the total reflux condensate or the reflux condensate fractions of corresponding boiling characteristics.

In case gasoline or gasoline-containing distillate from an external source is supplied, as previously described, to fractionator 15, it may serve to partially cool and assist fractionation of the vaporous conversion products with which it commingles in this zone, any light gasoline fractions corresponding in boiling characteristics to the light gasoline fractions recovered as the overhead product from fractionator 15 being commingled therewith and subjected to the same subsequent treatment, previously described, while any heavier fractions commingle with the reflux condensate formed in fractionator 15 and are recovered or subjected to further treatment therewith.

As a specific example of an operation of the process herein provided as it may be conducted in an apparatus of the character illustrated and above described: Vaporous products formed by the pyrolytic conversion of hydrocarbon oils and previously separated from non-vaporous residual

products of the cracking operation are supplied to fractionator 3 at a temperature of about 750° F. and a superatmospheric pressure of approximately 100 pounds per square inch. Charging stock for the cracking operation, which is an oil boiling above the range of gasoline, is preheated by means of heat recovered from the cracking system and introduced into fractionator 3 at a temperature of approximately 400° F. wherein it is separated, together with the condensed high-boiling fractions of the vapors, into light and heavy reflux condensates which are cracked in separate heating coils of the aforementioned cracking system under independently controlled conditions. A Mid-Continent straight-run gasoline of approximately 400° F. end-boiling point is supplied in part to fractionator 3 and in part to fractionator 15 in each of which zones it serves as a cooling and refluxing medium.

Vaporous products having an end-boiling point of approximately 400° F. and including substantially all of the straight-run gasoline supplied to fractionator 3, are removed as the overhead product from fractionator 13. A portion of this vaporous stream is supplied to partial condenser 18 wherein it is cooled to a temperature of approximately 250° F., the resulting condensate being returned in regulated quantities to the upper portion of fractionator 3 as a cooling and refluxing medium, while the uncondensed vapors and gases of the partial condensation step and the remaining portion of the overhead vaporous stream from fractionator 3 are supplied to fractionator 15 for further fractionation. The quantity of the materials in the overhead vaporous stream from fractionator 3 which is supplied to partial condenser 18, is automatically controlled in response to the temperature of the vaporous stream leaving fractionator 3 by means of a temperature controller (not shown) which actuates valve 17 in line 16, so that no substantial excess quantity of distillate is collected in accumulator 21. The quantity of distillate recirculated from accumulator 21 by means of pump 24 to the upper portion of fractionator 3 is automatically controlled in response to the liquid level in accumulator 21 by means of a liquid level controller (not shown) which may either vary the speed of pump 24 or vary the quantity of distillate discharged therefrom to fractionator 3, any excess being returned, for example, to accumulator 21 and the pump operating at a substantial constant speed.

The straight-run gasoline and gasoline conversion products supplied to fractionator 15 are separated by fractionation in this zone into a light vaporous fraction and a higher boiling condensate. The light vaporous fraction consists of substantially all of the normally gaseous components of the materials supplied to fractionator 15 and light gasoline fractions having an end-boiling point of approximately 260° F., which latter are of satisfactory antiknock value. The higher boiling condensate consists of heavy gasoline fractions boiling between approximately 260 and 400° F. These heavy gasoline fractions are also of satisfactory antiknock value but require chemical treatment to reduce their gum content and improve their color. The heavy gasoline fractions are sufficiently free of dissolved normally gaseous products that they do not require stabilization to reduce their vapor pressure.

The fractionated vaporous stream removed from the upper portion of fractionator 15 is

cooled in partial condenser 44 to a temperature of approximately 170° F. and regulated quantities of the resulting distillate are returned from accumulator 47 to the upper portion of fractionator 15 wherein they serve as a cooling and refluxing medium. The remainder of the distillate collected in accumulator 47 and the vapors and gases which are condensed in partial condenser 44 are directed to further cooling and condensation in sub-coolers 57 and 57' wherefrom the resulting distillate and uncondensed gases are directed to collection and separation in receiver 68. The light gasoline fractions collected in this zone contain a substantial quantity of dissolved gases and are stabilized, in the manner described, to reduce their vapor pressure to approximately 12 pounds per square inch, as determined by the Reid method, the stabilized light gasoline fractions being blended, without further treatment, with the treated and unstabilized high-boiling gasoline fractions recovered from fractionator 15 to form a 400° F. end-point gasoline which is a mixture of straight-run and cracked products having a satisfactory antiknock value and a vapor pressure of approximately 10 pounds per square inch.

The invention is, of course, not limited to the operating conditions nor to the specific mode of operation specified in the above example, since either or both may be varied considerably, as outlined in the foregoing description of the drawing, without departing from the scope of the invention.

I claim as my invention:

1. In a process wherein hot vaporous products resulting from the pyrolytic conversion of hydrocarbon oils and containing a substantial quantity of materials boiling within the range of gasoline are fractionated to condense therefrom fractions boiling above the range of gasoline, the combination of concomitant steps which comprise removing from the zone of said fractionation a vaporous stream consisting essentially of gasoline and normally gaseous products, dividing said stream into two portions of like boiling range and subjecting one of said portions to condensation, returning resultant condensate in regulated quantities to the zone of said fractionation wherein it serves as a cooling and refluxing medium, further fractionating the other portion of said stream to separate the components thereof into a vaporous fraction, consisting primarily of light gasoline fractions and normally gaseous products, and a higher boiling condensate comprising heavy gasoline fractions, removing said higher boiling condensate from the second mentioned fractionating step, partially condensing said vaporous fraction from the second mentioned fractionating step and returning resultant condensate in regulated quantities to said second mentioned fractionating step wherein it serves as a cooling and refluxing medium, subjecting the vapors and gases remaining uncondensed by the last mentioned partial condensation step to sufficient further cooling to condense substantially all of their normally liquid components, separating the resulting distillate and uncondensed normally gaseous products, stabilizing the distillate to reduce its vapor pressure to the desired degree by liberating controlled quantities of dissolved normally gaseous products therefrom and recovering the resulting stabilized light gasoline fractions.

2. In a process wherein hot vaporous products resulting from the pyrolytic conversion of hydro-

carbon oils and containing a substantial quantity of materials boiling within the range of gasoline are fractionated to condense therefrom fractions boiling above the range of gasoline, the combination of concomitant steps which comprise removing from the zone of said fractionation a vaporous stream consisting essentially of gasoline and normally gaseous products, dividing said stream into two portions of like boiling range and subjecting one of said portions to condensation, returning resultant condensate in regulated quantities to the zone of said fractionation, wherein it serves as a cooling and refluxing medium, further fractionating the other portion of said stream in commingled state with distillate from an external source which contains a substantial quantity of both light and heavy gasoline fractions, separating the commingled materials by said further fractionation into a vaporous fraction, consisting primarily of light gasoline fractions and normally gaseous products, and a higher boiling condensate comprising heavy gasoline fractions, removing said higher boiling condensate from the second mentioned fractionating step, partially condensing said vaporous fraction from the second mentioned fractionating step and returning resultant condensate in regulated quantities to said second mentioned fractionating step wherein it serves as a cooling and refluxing medium, subjecting the vapors and gases remaining uncondensed by the last mentioned partial condensation step to sufficient further cooling to condense substantially all of their normally liquid components, separating the resulting distillate and uncondensed normally gaseous products, stabilizing the distillate to reduce its vapor pressure to the desired degree by liberating controlled quantities of dissolved normally gaseous products therefrom and recovering the resulting stabilized light gasoline fractions.

3. In a process for the treatment of hydrocarbon oils wherein hot vaporous products resulting from the pyrolytic conversion of hydrocarbon oils and containing a substantial quantity of materials boiling within the range of gasoline are fractionated to condense therefrom fractions boiling above the range of gasoline, the combination of concomitant steps which comprise commingling with the vaporous products undergoing fractionation, hydrocarbon oil distillate from an external source which contains at least a substantial quantity of gasoline, removing from the zone of said fractionation a vaporous stream consisting essentially of normally gaseous products and the gasoline components of both said vaporous products and said distillate, dividing said stream into two portions of like boiling range and subjecting one of said portions to condensation, returning resulting condensate in regulated quantities to the zone of said fractionation wherein it serves as a cooling and refluxing medium, further fractionating the other portion of said stream to separate the same into a vaporous fraction, consisting primarily of light gasoline fractions and normally gaseous products, and a higher boiling condensate comprising heavy gasoline fractions, removing said higher boiling condensate from the second mentioned fractionating step, partially condensing said vaporous fraction from the second mentioned fractionating step and returning resultant condensate in regulated quantities to the second mentioned fractionating step wherein it serves as a cooling and refluxing medium, sufficiently

further cooling the vapors and gases remaining uncondensed by the last mentioned partial condensation step to condense substantially all of their normally liquid components, separating the resulting distillate and uncondensed normally gaseous products, stabilizing the distillate to re-

duce its vapor pressure to the desired degree by liberating dissolved normally gaseous products therefrom and recovering the resulting stabilized light gasoline fractions.

LYMAN C. HUFF.
